[57] **CLAIM**

The ornamental design for a tilted drain board, as shown and described.

DESCRIPTION

FIG. 1 is a perspective view of a tilted drain board showing my new design;

FIG. 2 is a left side elevational view, the right side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken lines depicting a dish rack are for illustrative purposes only and form no part of the claimed design.
